UNITED STATES PATENT OFFICE

127,330

DESIGN FOR A SHADE GUIDE STAND OR SIMILAR ARTICLE

Joseph M. Purcell, Brookline, Mass., assignor to
Ideal Tooth Incorporated, Cambridge, Mass., a
corporation of Massachusetts

Application March 13, 1941, Serial No. 99,566

Term of patent 14 years

To all whom it may concern:

Be it known that I, Joseph M. Purcell, a citizen of the United States of America, residing at Brookline, in the county of Norfolk and Commonwealth of Massachusetts, have invented a new, original, and ornamental Design for a Shade Guide Stand or Similar Article, of which the following is a specification, reference being had to the accompanying drawing, forming a part thereof.

Fig. 1 is a top plan view of a shade guide stand or similar article embodying my new design;

Fig. 2 is a side elevation thereof; and

Fig. 3 is a sectional view on the line 3—3 of Fig. 2.

I claim:

The ornamental design for a shade guide stand or similar article, substantially as shown.

JOSEPH M. PURCELL.
